UNITED STATES PATENT OFFICE.

WILLIAM F. BETHMANN, OF BUFFALO, NEW YORK.

RAZOR SHARPENER.

Application filed December 21, 1921. Serial No. 523,977.

To all whom it may concern:

Be it known that I, WILLIAM F. BETHMANN, a citizen of the United States, residing at Buffalo, in the county of Erie and State of New York, have invented new and useful Improvements in Razor Sharpeners, of which the following is a specification.

This invention relates to a machine for sharpening straight edge razors and the blades of safety razors and the like.

One of the objects of the invention is to provide an efficient machine of this character which is capable of working simultaneously on both sides of the cutting edge of the blade to expedite the sharpening operation.

Another object is to provide a machine which automatically sharpens the edge of the razor blade to its proper angle or contour.

20 A further object is to provide the machine with means for supporting and guiding the razor as it is reciprocated across the sharpening devices.

Still further objects of the invention are 25 to provide a razor sharpener which is simple and compact in construction, which is not liable to get out of order, and which can be manufactured at a moderate cost.

In the accompanying drawings:

30 Figure 1 is a side elevation of the improvement. Figure 2 is a transverse vertical section on line 2—2, Fig. 1. Figure 3 is an enlarged transverse section on line 3—3, Fig. 1. Figure 4 is an enlarged horizontal section on line 4—4, Fig. 1. Figure 5 is an enlarged vertical section on line 5—5, Fig. 2. Figure 6 is a perspective view of a type 35 of holder used in connection with sharpening safety razor blades by this machine.

40 Similar characters of reference indicate corresponding parts throughout the several views.

The working parts of the machine are mounted on a base 10 and an upright frame 45 11 arranged at one end of the base.

Arranged side by side within this frame are one or more pairs of endless parallel strops or belts 12, 13 made of leather or other similar flexible material, one strop of 50 each pair passing around a comparatively larger upper pulley 14 and around a small lower pulley 15, while the companion strop passes around a small upper pulley 16 and around a comparatively large lower pulley

17. The upper pulleys 14, 16 are mounted 55 on a horizontal shaft 18 journaled in the upper end of the frame 11, and the lower pulleys 15, 17 are mounted on a similar shaft 19 suitably journaled in the lower end of said frame. This arrangement results in 60 the straight stretches of the strops of each pair being inclined in opposite directions or crossing each other edgewise to form a substantially V-shaped throat or crotch 20 at a point between the axes of the pulley shafts 65 18 and 19, as shown in Figs. 2 and 3. The razor blade 21 to be sharpened is held in a substantially horizontal position and is reciprocated crosswise of and between the opposing inner and outer faces of the companion strops of each pair with its cutting edge seated in the respective throats 20.

Any suitable means may be employed for transmitting motion to the shafts 18 and 19 to move the strops 12, 13 in the same direction and at the same speed. As shown in the drawings, however, these means preferably consist of an electric motor 22 mounted on the base 10 and having its shaft 23 connected with the lower pulley shaft 19 by a 70 suitable coupling sleeve 24. Mounted on the opposite end of said lower shaft and the corresponding end of the upper pulley shaft 18 are equalizing pulleys 25 around which a transmission belt 26 passes, whereby said 75 pulley shafts are rotated in the same direction and at the same speed. In order to cause the several strops to travel at the same speed, one of the pulleys of each strop is fixed on its shaft while the other is loosely 80 mounted on its shaft, whereby all of the large pulleys 14, 17 or all of the small pulleys 15, 16 are directly driven by their respective shafts. In the drawings, the large pulleys 85 are shown fixed to their shafts by set screws 27, while the small pulleys are loosely mounted on said shafts. By this arrangement, the strops 13 are driven by the large lower pulleys 17 fixed on the shaft 19 connected with the motor shaft 23, while the 90 strops 12 are driven by the large upper pulleys 14 fixed on the shaft 18 which is driven at the same speed as said shaft 19 through 95 the medium of the transmission belt 26.

As indicated by the arrows in Fig. 3, the 100 pulleys are driven in a counter-clockwise direction to move the strops downwardly toward the cutting edge of the razor blade.

The upper pulley shaft 18 is preferably mounted in self-adjusting bearing blocks 28 which are mounted in vertical guideways 29 arranged in the upper side portions of the frame 11, as shown in Figs. 2 and 5. Interposed between the bottoms of these bearing blocks and the opposing ends of the guideways are springs 30 which constantly tend to raise said blocks and the shaft to keep the strops taut.

Any suitable means may be employed for supporting the razor as it is reciprocated across the opposing faces of adjacent strops and also for limiting its stroke in either direction. The preferred means for accomplishing this result are shown in the drawings and are constructed as follows:

Arranged on one side of the frame 11 between the upper and lower pulley shafts is a vertical guide tube 31 which may be attached to said frame by screws 32 and which is provided in its front side with an upright opening 33. Yieldingly supported in this guide tube is a plunger 34 provided with a horizontal rest pin 35 which is located substantially in transverse alignment with the throats 20 and which extends forwardly through the opening 33 in said tube, as shown in Figs. 1, 2 and 4. Interposed between the plunger and a pin 36 in the lower end of the guide tube is a comparatively light coil spring 37, which, when it is expanded or normal position, shown in Fig. 1, permits the plunger to assume a position near the upper end of its tube so that the pin 35 is located a suitable distance above the bottom of the throats 20 produced by the intersecting strops 12, 13. The shank 38 of the razor is adapted to rest on said pin 35 as it is reciprocated manually across the opposing faces of the strops. The other side of the frame is provided with a plate 39 which may be secured thereto in any suitable manner, and which is provided at one edge with a forwardly-projecting upright stop flange 40 located in the path of travel of the razor and adapted to limit its movement in one direction. The extent of movement of the razor in the opposite direction is limited by the pin 35 against which the end of the razor adjacent its shank is adapted to abut, as shown in Fig. 1.

In the operation of this razor sharpener, assuming the strops to be in motion, the razor is inserted between the opposing inner and outer faces of the pairs of oppositely inclined strops with its cutting edge seated in the V-shaped throats 20 formed by adjacent strops and its shank resting on the pin 35 of the yieldable plunger 34. The razor is then moved manually back and forth across these strops which automatically adjust themselves to the cutting edge of the razor and which operate on opposite sides of its cutting edge from end to end

thereof, the stroke of the razor being limited in either direction by said pin 35 and the stop flange 40. The pressure of the strops against the opposite sides of the cutting edge may be regulated at will by forcing the razor downward more or less into the throats 20. The arrangement of the strops enables the edge of the razor to be sharpened to its proper angle or contour without requiring any special attention on the part of the operator. When the razor is sharpened, it is removed by simply lifting its inner end clear of the supporting pin and withdrawing it from between the strops.

If desired, the strops may be provided with a suitable sharpening compound on their working faces.

In sharpening a razor with this device no honing is required and the sharpening and stropping are accomplished in one and the same operation. Furthermore, the intersecting strops operate simultaneously and adjust themselves automatically on both sides of the cutting edge of the razor, thereby materially expediting the sharpening of the razor.

This machine is also capable of sharpening the detachable blades of safety razors by providing a suitable holder for receiving them. One form of holder which may be employed is shown in Fig. 6, and comprises a pair of spring-pressed jaws 41, 42, pivoted together midway of their width by a rod 43. One of the jaws is provided with a handle 44 for reciprocating the holder and its blade across the faces of the strops.

I claim as my invention:

1. A razor-sharpener, comprising a frame, and a pair of traveling stropping belts arranged side by side in said frame, said belts having straight, flexible stretches inclined in opposite directions and crossing each other edgewise thereof to form an angular throat between them for receiving the cutting edge of a razor.

2. A razor-sharpener, comprising a frame, opposing pairs of pulleys mounted on said frame, the pulleys of each pair being in spaced relation and a pair of endless stropping members passing around said pulleys and crossing each other at a point between them.

3. A razor-sharpener, comprising a frame, a plurality of alternately arranged large and small pulleys mounted at opposite ends of said frame, each small pulley being arranged opposite one of said large pulleys, and endless stropping members each passing around an opposing set of said large and small pulleys.

4. A razor-sharpener, comprising a frame, upper and lower pairs of large and small pulleys mounted in said frame, each small pulley being arranged opposite one of said large pulleys, and a pair of endless stropping

members, one passing around the large upper and the small lower pulley of a pair, and the other of said members passing around the small upper and the large lower pulley 5 of the other pair.

5. A razor-sharpener, comprising a frame, upper and lower shafts journaled in said frame, a pair of large and small pulleys mounted on each of said shafts, one pulley 10 of each pair being fixed on its shaft and the other being loose, endless stropping members passing around said pulleys, and means for driving said shafts to move said members in the same direction and at the 15 same speed.

6. A razor-sharpener, comprising a frame, upper and lower shafts journaled in said frame, one of said shafts being mounted in self-adjusting bearings, a pair of pulleys 20 mounted on each of said shafts, and a pair of endless stropping members passing around said pulleys, said members crossing each other at a point between the axes of said shafts.

25. 7. A razor-sharpener, comprising a frame, a pair of movable stropping members arranged side by side in said frame, said stropping members including straight stretches which cross each other edgewise thereof, 30 forming an angular stropping throat between them, and means on said frame for guiding and limiting the extent of movement of the razor as it is reciprocated lengthwise across the working faces of said stropping 35 members.

8. A razor-sharpener, comprising a frame, a pair of movable stropping members arranged side by side in said frame, said stropping members including straight 40 stretches which cross each other edgewise thereof, forming an angular stropping throat between them, and a yieldable razor-support on said frame at one side of the stropping members, said support yieldingly

resisting movement of the razor toward the 45 apex of the throat.

9. A razor-sharpener, comprising a frame, a pair of movable stropping members arranged side by side in said frame, said members including straight stretches which cross 50 each other edgewise thereof to form an angular throat between them for receiving a razor, a yieldable razor support on one side of said frame for yieldingly resisting movement of the razor toward the apex of said 55 throat, said support being constructed to limit the movement of the razor in one direction as it is reciprocated across the working faces of said stropping-members, and a stop-member on the opposite side of said 60 frame for limiting the movement of the razor in the opposite direction.

10. A razor-sharpener, comprising a frame, a pair of movable stropping members mounted in said frame to form an angular 65 throat between them for receiving a razor, and means on said frame for guiding and limiting the extent of movement of the razor as it is reciprocated across the working faces of said stropping members, comprising a 70 tubular member mounted on one side of said frame, a plunger yieldingly supported in said tubular member and having a pin thereon, and a stop-member on the opposite side of said frame arranged in the path of movement of the razor.

11. A razor-sharpener, comprising a frame, a pair of movable stropping members arranged side by side in said frame and crossing each other edgewise to form an 80 angular throat between them for receiving a razor, and a yieldable support on said frame with which the razor shank is adapted to engage, said support being substantially 85 in transverse alignment with said throat and located at one side of the stropping members.

WILLIAM F. BETHMANN.
